ONE-HANDED LIP-STICK

Edward S. Cornell, Jr., Larchmont, N. Y.

Application March 25, 1933, Serial No. 662,721

8 Claims. (Cl. 206—56)

My present invention relates to holding and dispensing devices, and more particularly to an improved device of this character for holding cosmetics and the like, such as lipsticks, and for dispensing thereof by manipulating the device with one hand.

A novel feature of my invention is the utilization of a casing which is open at one end, and which casing houses a lipstick mounted on means for propelling the lipstick outwardly through the open end and retracting such lipstick to a place within the casing.

A feature also of my invention is the utilization of a rotatable means at the open end of the casing, comprising essentially an annular chamber mounted on or associated with the propelling and retarding means for the cosmetic stick.

A feature also of my invention is the utilization of a closure means for the open end of the casing, operable on the rotation of the annular member in one direction to completely expose the open end of the casing and to thus permit the propelling of the end of the cosmetic stick to the desired point without the casing, and on the rotation of the annular member in the opposite direction for the purpose of retracting the cosmetic stick within the casing to again close the open end of the casing.

A feature of my invention also is the utilization of a form of shutter and operating means therefor for insuring the complete opening of the open end of the casing before the stick of cosmetic has been propelled to a point in proximity to the underface of the cover and to initiate closing of the cover only after the stick of cosmetic has been retracted to a point completely within the casing.

My invention also has many novel features which will be apparent to those skilled in the art as the description of the invention progresses.

In the accompanying drawing illustrating a preferred form of my invention,

Fig. 1 is a vertical sectional elevation of a cosmetic holding device made according to my invention, the upper end of such figure being shown in elevation;

Fig. 2 is a top plan view of Fig. 1;

Fig. 3 is a sectional elevation on an enlarged scale on the line 3—3 of Fig. 2, showing the upper end of the device;

Fig. 4 is a sectional plan view on the line 4—4 of Fig. 3, and with the cover or shutter in closed position;

Fig. 5 is a view similar to Fig. 4 and showing the shutter or cover in open position; and

Fig. 6 is a sectional plan view on the line 6—6 of Fig. 1.

Referring to the drawing, there is shown a cylindrical outer casing 10 having the lower end permanently closed by a bottom plate 11, which preferably though not necessarily is formed integral with the outer casing 10. The upper end of the casing 10 is flanged outwardly in a horizontal plane as indicated by the reference numeral 12 and the flange portion 12 is cut away, 10 as indicated by the reference numeral 13, at various points about its periphery to define rectangular members 14. The rectangular members 14 are thus equally spaced about the periphery of the flange portion 12 and such rectangular portions 14 lie parallel to and extend upward from— as viewed in Fig. 1—the outer casing 10.

Fitting within the outer casing 10 is a cylindrical member 15, such cylindrical member having a close fit within the casing 10 so that the friction between the casing 10 and the cylindrical member 15 is ordinarily sufficient to prevent rotation of such cylinder 15 within the casing 10. This cylindrical member 15 extends from the top face of the bottom or closure 11 to a point flush with the inner upper surface of the flange portion 12, as clearly shown in Figs. 1 and 3.

Also, this cylindrical member 15 is provided with grooves 15a, of which there may be a plurality and in this case as shown, I have utilized three such grooves. Such grooves 15a lie parallel to each other and are symmetrically located about the cylindrical member 15 and extend from the bottom thereof upward to a point slightly beyond the center of the length of the casing 10 and parallel to the axis of such casing 10.

Fitting into the interior of the cylindrical member 15 and having an outer diameter bearing such relation to the internal diameter of the cylindrical member 15 as to allow of free rotative movement thereof is a propelling cylinder 16, the lower end of the member 16 extending into the cylindrical member 15 to a point considerably below the center of the length of the outer casing 10. On the surface of the propelling member 16 is formed, preferably in the form of a bead, a helical groove 17 for a purpose to be hereinafter described.

The propelling member 16 has at the top thereof, and preferably formed integral therewith, an annular chamber 18, the underface of the annular chamber 18 engaging with and being rotatable on the upper surface of the flange 12 and the upper edge of the cylindrical member 15, as

clearly shown in Fig. 3. The upper end of the annular chamber 18 is closed by an inwardly extending flange member 19 which is provided at its center with a central perforation 20 slightly larger in diameter than the stick of cosmetic 21 so as to allow such stick of cosmetic to freely pass therethrough as occasion requires.

Formed in the upper surface of the inwardly extending member 19 is a groove 22 for a purpose to be hereinafter described.

The annular chamber 18 on the upper end of the propelling member 16 is housed in position by a member comprising an annular plate 23 provided with an inwardly and downwardly extending flange 24 defining an opening 25 of approximately the size of the opening 20 in the member 19. At the outer periphery of the member 23 is a downwardly extending cylindrical member 26 and at the lower end of the downwardly extending cylindrical member 26 is an outwardly extending flange member 27 cut away at spaced portions about its periphery at 28, such cut away portions corresponding in size, position and number to the cut away portions 13 in the flange 12. At the outer periphery of the flange 27 are downwardly extending rectangular members 29, equal in size, number and arrangement to the upwardly extending rectangular members 14 on the flange 12. At the lower end of the downwardly extending rectangular members 29 is formed integral therewith a flange 30 which is spun over, as clearly shown in Fig. 3, to engage with the underside of the flange 12, and thus secure the annular chamber 18 in position as shown in Fig. 3, but which allows free rotation without undue play of the annular chamber 18 and the associated propelling member 16.

Referring to Fig. 3, it will be noted that the upper surface of the member 19 and the under surface of the annular member 23 together with the flange 24 and cylindrical member 26 form a housing in which is located a cover or shutter. Such cover or shutter is composed of component elements, shown in the form of a plurality of plates 31, 32, 33, and 34, although it is obvious that the number of such plates may be increased or diminished as may be desired. Such plates 31 to 34, inclusive, are pivotally mounted at a point adjacent their ends on a common shaft 35 riveted to the annular plate 23, the above referred to groove 22 in the member 19 providing clearance for the free movement of the lower riveted end of the shaft 35 upon rotation of the member 19 relative to the plate 23. The plates 31 to 34, inclusive, when in extended position with respect to each other about the common shaft 35 slightly overlap each other, as clearly shown in Fig. 4, and the combined area of such extended plates 31 to 34, inclusive, is sufficient to completely close the openings 25 and 20. The plate 31 is provided with a notched member 36 adjacent the pivot point of such plate. The plates 32, 33 and 34 are each provided adjacent the common pivot 35 with a tooth 37, 38, and 39, respectively.

Formed integral with the inwardly extending member 19 of the annular chamber 18 by striking up a portion of the metal therefrom is a pin 40 which lies in the path of the notched member 36 and with the teeth 37, 38 and 39 or conversely stated, the notched member 36 and the teeth 37, 38, and 39 lie in the path of rotation of the pin 40. It is obvious therefore that assuming the plates 31, 32, 33, and 34 to be in the extended position or in a position to close the opening 25, that if the annular chamber 18 is rotated in the

direction of the arrow as shown in such Fig. 4, that the pin 40 will first engage the notched member 36, rotating the plate 31 slightly about the common shaft 35 in a counterclockwise direction and that the pin 40 will next engage with the tooth 37 and will therefore in turn rotate the plate 32 and further rotate the plate 31. Continued rotation of the annular member 18 will cause the pin 40 to come successively into engagement with the teeth 38 and 39, thus moving the plates 31 to 34, inclusive, from the extended or closed position into the open position, as shown in Fig. 5, thus exposing to view the stick of cosmetic 21 now visible through the holes 25 and 20, and further rotation of the annular chamber 18 will have no further effect on the plates 31 to 34, inclusive, the pin 40 merely rotating with the annular chamber 18.

Slidably mounted within the interior of the propelling member 16 is a cylindrical member 41 and this cylindrical member 41 is provided adjacent its bottom edge and about the periphery with radially extending members 42, such members having a sliding fit in the slots 15a, so that although the cylindrical member 41 may be moved longitudinally of the outer casing 10, it is restricted to rectilinear movement and therefore cannot rotate.

About the surface of the cylindrical member 41 is arranged a helical member 43 which engages with the helical member 17 formed in the surface of the propelling member 16. The cylindrical member 41 is of a length slightly less than half the length of the outer casing 10, as clearly shown in Fig. 1, and adjacent to the upper end 35 of the cylindrical member 41, which is open at both ends, are inwardly extending members 44 preferably formed integral with and of the same metal of the cylindrical member 41.

The members 44 form a limiting means for the holding device 45 for the stick of cosmetic 21, such holder being formed of a cylindrical cup having integrally formed radially extending loops 46 and the bottoms of which rest on the inwardly extending members 44.

Formed in the propelling member 16 and extending upwardly and helically from the lower open end thereof are the grooves or slots 47, such grooves or slots 47 being of a width substantially equal to the width of the slots 15a, and of the same pitch as the pitch of the helical grooves or beads 17 and 43. Also, such grooves or slots 47 are equal in number to the number of slots 15a and therefore to the number of outwardly extending members 42 at the lower end of the cylindrical member 41.

The plates 31 to 34 of the shutter or cover and the position of the pin 40 with relation to the notched end 36 and the teeth 37, 38, and 39, are so proportioned relative to the pitch of the helical bead 17 of the propelling member 16 that the pin 40 will move the shutter plates or cover members 31 to 34 from the closed position shown in Fig. 4 to the open position shown in Fig. 5, before the upper end of the stick of cosmetic 21 will have travelled the distance between such open end and the under surface of the shutter plates.

Assuming, therefore, that the device has been constructed and assembled as above described and that the parts are in the position shown in Figs. 1 and 3, for example, rotation of the annular chamber 18 will simultaneously cause an upward movement of the stick of cosmetic 21 and a rotative movement of the shutter plates 31 to 34, inclusive, about the common shaft 35.

The pin 40 thus engaging with the notched plate 36 and with the teeth 31, 38, and 39 will move the plates 31 to 34, inclusive, from the position shown in Fig. 4 to the position shown in Fig. 5, before the upper end of the stick of cosmetic 21 has reached the plane in which lies the lowermost of the plates 31 to 34, in this case the plate 34. Continued rotation of the angular chamber 18 will rotate the propelling member 16 and the stick of cosmetic 21 will be moved through the holes 25 and 20 outward, axially of the outer casing 10.

It will be noted that the lower end of the propelling member 16 is below the upper end of the slots 15a and that ordinarily therefore the outwardly extending members 42 would strike the lower edge of the propelling member 16 and thus limit the upward movement of the cylindrical member 41 and therefore the outward movement 20 of the stick of cosmetic 21 axially of the outer casing 10.

As at such position of the cylindrical member 41 a considerable portion of the stick of cosmetic 21 remains within the limits of the outer casing 10, the rotation of the propelling member 16 will bring the helical slots 47 into registry with the outwardly extending members 42, and therefore the members 42 register from this point all simultaneously with the slots 15a and with the helical grooves 47, thus permitting the holder 45 of the cosmetic stick 21 to move upwardly to a point closely adjacent the upper and now open end of the casing 10 and allowing the user of the device to either remove the holder 45 with the now practically used up stick of cosmetic 21 and insert a new one or to permit the user to use practically every vestige of the cosmetic stick 21.

While I have necessarily shown and described the preferred embodiment of my invention somewhat in detail, it is to be understood that I may vary the size, shape and arrangement of parts comprising my invention within relatively wide limits without departing from the spirit of the invention.

I claim:

1. In a receptacle, the combination of an outer casing open at one end, a carrier member for the article to be dispensed located within the casing, an operating member located within the casing for propelling the end of the article to be dispensed without the limits of the casing and for returning such article to a point within the casing, shutter means mounted at the open end of the casing, said shutter means including a plurality of shutter elements mounted in pivotal relation to one another, and common means coordinated with said operating member for individually and successively engaging said shutter elements to move the same into vertically superposed relation with one another to effect opening of the casing at its open end.

2. In a receptacle, the combination of an outer casing open at one end, a carrier member for the article to be dispensed located within the casing, an operating member located within the casing for propelling the end of the article to be dispensed without the limits of the casing and for returning such article to a point within the casing, pivotal means mounted at the open end of the casing, closure means comprising a plurality of closure elements mounted in pivotal and vertically superposed relation to one another, and common means actuated by said propelling operating member individually and successively en-

gaging said closure elements for moving the same to open and closed positions of the closure means respectively.

3. In a receptacle, the combination of an outer casing open at one end, a carrier member for the article to be dispensed located within the casing, an operating member located within the casing for propelling the end of the article to be dispensed without the limits of the casing and for returning such article to a point within the casing, a pivot-member mounted at one side of and adjacent the open end of the casing, a plurality of shutter elements mounted in vertically superposed relation on said pivot member, and common means coordinated with said propelling operating member for individually and successively moving said shutter elements to their open and closed positions respectively.

4. In a receptacle, the combination of an outer casing open at one end, a carrier member for the article to be dispensed located within the casing, an operating member located within the casing for propelling the end of the article to be dispensed without the limits of the casing and for returning such article to a point within the casing, pivotal means secured to and adjacent the open end of the casing and extending outwardly relative to the casing, a plurality of vertically superposed component shutter elements mounted on said pivotal means, and common means actuated by the propelling operating member individually and successively engaging said component shutter elements to move the same to their open and closed positions respectively.

5. In a receptacle, the combination of an outer casing open at one end, a carrier member for the article to be dispensed located within the casing, said member having an outer diameter less than the inner diameter of said outer casing, an operating member located within the casing for propelling the end of the article to be dispensed without the limits of the casing and for returning the article to a point within the casing, a pivotally mounted multi-part shutter for the open end of the casing, said multi-part shutter comprising mutually pivoted shutter elements vertically superposed upon one another, and common means carried by the article propelling and repelling means for simultaneously propelling the article and individually and successively engaging the shutter parts to provide a clear path for the article to be dispensed.

6. In a receptacle, the combination of an outer casing open at one end, a carrier member for the article to be dispensed located within the casing, said member having an outer diameter less than the inner diameter of said outer casing, an operating member located within the casing for propelling the end of the article to be dispensed without the limits of the casing and for returning the article to a point within the casing, a multi-part shutter located at the open end of the casing, said multi-part shutter comprising shutter elements vertically superposed upon one another, and mutually pivoted relative to said outer casing, and means associated with the article propelling and repelling means for moving the shutter to closed position only after the outer end of the article to be dispensed has been withdrawn to a point within the casing, said shutter moving means including an arm actuated by said propelling and repelling operating member individually and successively engaging said extensions of the shutter parts to effect movement of

the same to their open and closed positions respectively.

7. In a receptacle, the combination with an outer casing open at one end, of a slotted hood secured to the open end of the outer casing and provided with a central perforation in alignment with the longitudinal axis of the casing, an operating member rotatably mounted within the casing and provided with a perforation at its upper end in association with the perforation in the hood member, article carrying means mounted within the casing and operated upon by the cylindrical member to propel the article to be dispensed to a point without the casing and to be repelled to a position within the casing, and a shutter at the open end of the outer casing comprising a plurality of arcuate members arranged in superimposed position with respect to each other and pivotally mounted on the hooded member and means carried by the rotatable member cooperating with the arcuate shutter members to rotate the same about the pivot point to expose the aligned perforations in the hooded member and in the rotatable cylindrical member to thereby permit movement of the article to be dispensed from the casing.
8. In a receptacle, the combination with an outer casing open at one end, a slotted hood member secured to the open end of the casing, a cylindrical member located within the outer casing and held thereto against relative move-

ment with respect therewith by friction, said member being provided with a plurality of longitudinally spaced linear slots arranged around its periphery, a rotatably mounted cylindrical member rotatably mounted within the outer casing and provided at its upper end with an annular member rotatably mounted within the slotted hood member, the rotatably mounted member and the hood member being provided with aligned cylindrical perforations in alignment with the axis of the outer casing, a helical groove formed in the surface of the rotatable cylindrical member, article holding means provided with a helical groove cooperating with the helical member in the rotatable means and with means for engaging the linear slots in the fixed member within the outer member, a shutter normally closing the open end of the outer casing and comprising a plurality of members arranged in superimposed relation to each other and pivotally mounted on the hooded member at one side of the perforation therethrough, and means on the rotatable member for engaging with the shutter members whereby the shutter members are moved from the perforation closing position to a completely open position simultaneously with the advance of the article to be dispensed but in advance of the arrival of the end of the article to be dispensed in a plane passing through the lowermost of the members of the shutter.

EDWARD S. CORNELL, JR. 30
